UNITED STATES PATENT OFFICE.

FELIX D. RENAUD, OF CHICAGO, ILLINOIS.

FLASHING FOR PARAPET-WALLS.

1,154,435.

Specification of Letters Patent. Patented Sept. 21, 1915.

Application filed May 29, 1915. Serial No. 31,178.

To all whom it may concern:

Be it known that I, FELIX D. RENAUD, a citizen of the United States, and a resident of Chicago, in the county of Cook and State of Illinois, have invented a new and Improved Flashing for Parapet-Walls, of which the following is a full, clear, and exact description.

My invention relates to flashings and it has for its object to provide an inexpensive and durable flashing particularly well adapted for protecting felt and similar roofs where they join a parapet wall.

Additional objects of the invention will appear in the following specification in which the preferred form of my invention is disclosed.

In the drawings similar reference characters refer to similar parts in all the views in which—

Figure 1 is a transverse sectional view showing my invention used to connect a roof with a parapet wall; and Fig. 2 is a perspective view of the block used for my flashing.

It is the practice in many localities to run felt roofing at parapet walls from two to six inches high and secure the roofing in this position with a wooden lath nailed to a mortar joint. This is not durable and while other flashings have been employed which are satisfactory they are often objected to because of their expense.

My flashing is not only effective but it is inexpensive to manufacture and may be made use of without employment of skilled labor.

It will be seen that with my flashing I take felt or other similar roofing A and turn it up at B so that it may rest against the inner side of a parapet wall C. I then make use of a metal lath D and press it against the turned up portion E of the roofing, the nails G being employed which are driven through the metal lath D, through the turned up portion E of the roofing and into the mortar joint at H in the parapet wall C. The metal lath D is provided with an upwardly and outwardly extending flange J which is cemented in a recess K in a flashing block M. The plastic cement not only serves to secure the flange J in the recess K in the flashing block M, but it also serves to fill in openings between the metal lath and the flashing block M which may be occasioned by unevenness of the parapet wall C, the turned up portion E of the roofing A or the

lath D. It will be observed that the bottom of the flashing block M is rounded at T so that a smooth surface will press against the felt or other roofing at B. This flashing block M is secured at its base to the roofing A with coal tar pitch or similar material. I then fill in the space at the top of the flashing block M with plastic cement O, the plastic cement resting against the parapet wall C. This serves to keep out water at the point of contact. When this has been done, the roof is mopped with pitch, and gravel is thrown thereon while the pitch is hot, and as this pitch and gravel are disposed at P against the outer side of the flashing block M, the base of the flashing block is held in position. The parapet wall and the flashing block are also mopped with pitch so that the whole is water proof.

As an additional means of keeping water away from the flashing, I propose to use a strip of water proofing R to be laid dry on the top of the second or third course of bricks in the parapet wall, this piece of water proofing being disposed in the rear of the flashing so that if bricks become broken or chipped or the mortar joints wash out, it will be impossible for the rain to work back beyond the flashing between the bricks to cause a leak.

The roofing A is, of course, disposed on the roof S of the building.

I prefer to construct the flashing block M of the following materials: one-third torpedo sand, one-third fine crushed limestone, and one-third Portland cement, but it can be made of terra cotta or other suitable material.

Having thus described my invention I claim as new and desire to secure by Letters Patent:

1. In combination with a roof and a parapet wall, a roofing laid on the roof and turned up at the parapet wall, a lath disposed against the outer side of the turned up portion of the roofing and secured to the turned up portion and to the parapet wall, an outwardly extending flange on the lath, a block disposed on the roofing and against the lath, the block having a recess in which the flange is disposed.

2. In combination with a roof and a parapet wall, a roofing laid on the roof and turned up at the parapet wall, a lath disposed against the outer side of the turned up portion of the roofing, a block disposed

on the roofing and against the lath, and means for holding the block in said position.

3. In combination with a roof and a parapet wall, a roofing laid on the roof and turned up at the parapet wall, a lath disposed against the outer side of the turned up portion of the roofing and secured to the turned up portion and to the parapet wall, an outwardly extending flange on the lath, a block disposed on the roofing and adjacent the parapet wall and secured to the said roofing, there being a recess in the block in which the flange is cemented.
4. In combination with a roof and a parapet wall, a roofing laid on the roof and turned up at the parapet wall, a lath disposed against the outer side of the turned up portion of the roofing and secured to the turned up portion and to the parapet wall, an outwardly extending flange on the lath, a block disposed on the roofing, and against

the lath, the block having a recess in which the flange is disposed, and water-proofing material disposed on the block, the water-proofing material extending outwardly and downwardly, and connecting the parapet wall with the top of the block at a distance from the wall. 25

5. A flashing block having its bottom curved upwardly at one side with a recess at its said side spaced from its bottom and with the top of the block extending over the recess and beyond the vertical plane at the said side of the block. 30

In testimony whereof I have signed my name to this specification in the presence of the two subscribing witnesses. 35

FELIX D. RENAUD.
